DEFENSIVE PUBLICATION

UNITED STATES PATENT AND TRADEMARK OFFICE

Published at the request of the applicant or owner in accordance with the Notice of Dec. 16, 1969, 369 O.G. 637. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

38 Sheets Drawing. 170 Pages Specification

Method and apparatus for providing programs for a computer in response to answers to a questionnaire, the questions being arranged in individually identified sets. The answers comprise entries that may be a selection from among predetermined alternatives may be a supplied stipulation. The entries are checked in accordance with predetermined verification instructions associated with the set identification. The checks include whether each stipulation is of a designated type and value range, and include whether a designated number or designated ones of the alternatives were selected, the designations being by the associated verification instructions. An error output indication is generated in response to the negative result of any of the checking steps. Each entry is then responded to in accordance with predetermined customizing instructions associated with the set identification to select ones of the customizing instructions as directed by the selected alternatives and stipulations and modify certain specifications in the customizing instructions as directed by the supplied stipulations. The customizing instructions refer to designated statements comprising specifications of program steps and may delete, select or modify the designated statements, subject to further deletion, selection or modification in accordance with other instructions. Those customizing instructions that are activated are sorted into the order of appearance of the statements and employed to delete, select and modify the designated statements in accordance with inclusion codes thereof. The statements comprising specifications of program steps are provided at an output in the form of an actual computer program or in the form of information translatable directly into a computer program.

REPORT DESIGN
COMPLETION INSTRUCTIONS & CUSTOMER SPECIFICATIONS

TOTALS SECTION - EXPLANATION OF QUESTIONS

*****
* THIS SECTION PROVIDES INFORMATION NECESSARY TO CORRELATE CONTROL FIELD CHANGES WITH CONTROL TOTALING, TTOTALING, PAGE *
* CONTROL AND TOTAL LINE PRINTING.
*****

360. RESPOND WITH THE MAXIMUM NUMBER OF CONTROL LEVELS THAT THIS PROGRAM MUST CONSIDER TO DETERMINE TOTALS AND PAGE ADVANCES (NOT INCLUDING FINAL TOTALS).
365. IF DETAIL LINES ARE NOT TO BE PRINTED RESPOND WITH AN "X". THE TOTAL LINES WILL BE PRINTED IN ACCORDANCE WITH T4F SPACING SPECIFIED IN QUESTION 350.
366. TOTALS WILL AUTOMATICALLY PRINT IN FIXED TOTAL LINE FORMAT - 10 CHARACTER ID, 5 CHARACTER VALUE, NINE 13 CHARACTERS TOTALS. ALTERNATIVELY, IF THIS QUESTION IS ANSWERED, THE TOTALS WILL BE POSITIONED UNDER THE COLUMNS BEING TOTALED. T4F USES MUST ALLOW 2 POSITIONS BETWEEN THE FIELDS TO PREVENT OVERLAPPING. NO TOTALS WILL BE PRINTED IN PRINT POSITIONS 1 THRU 15.
370. INDICATE WHICH OF THE CONTROL FIELDS INDICATED IN THE INPUT-OUTPUT SECTION ARE FOR PAGE ADVANCE PURPOSES BY LISTING THE "CL" NUMBERS SHOWN IN THE INPUT-OUTPUT SECTION.
380. INDICATE WHICH OF THE CONTROL LEVEL VALUES ARE TO CAUSE A TOTAL LINE TO BE PRINTED AND THE FORM TO BE ADVANCED TO THE NEXT PAGE BY LISTING THE "CL" VALUE ASSIGNED IN THE INPUT-OUTPUT SECTION IN THE RESPONSE BOXES.
390. IF CONTROL LEVELS (QUESTION 360) WERE REQUESTED, RESPOND TO THIS QUESTION. IF TOTAL LINES ARE TO BE PRINTED ON SPECIFIC PRINT LINES, RESPOND WITH A 3 DIGIT NUMBER INDICATING WHICH LINE EACH TOTAL LINE IS TO OCCUPY. IF TOTAL LINES REQUIRE SPACING WHICH IS DIFFERENT THAN THE REGULAR SPACING OF THE REPORT, RESPOND WITH "SN" WHERE N IS THE NUMBER OF BLANK LINES TO BE INSERTED BEFORE AND AFTER THE TOTAL LINE. IF THERE IS NO RESPONSE TO THIS QUESTION, THE PROGRAM WILL PRINT THE TOTAL LINES ON THE NEXT AVAILABLE LINE.
400. IF CONTROL LEVELS (QUESTION 360) WERE NOT REQUESTED, INDICATE ON WHICH LINE EACH "FINAL TOTAL LINE" REQUIRED IS TO BE PRINTED.
410. IF CONTROL TOTALS (QUESTION 360) WERE REQUESTED, THE GENERATION OF THE "FINAL TOTAL LINE" IS AUTOMATIC. INDICATE HERE WHERE IT IS TO BE PRINTED. IF THERE IS NO RESPONSE TO THIS QUESTION, THE "FINAL TOTAL LINE" WILL NOT BE PRINTED. AS IN QUESTION 390, "SN" MAY BE USED.
